UNITED STATES PATENT OFFICE.

ROBERT J. MURRAY, OF PHILADELPHIA, PENNSYLVANIA, ASSIGNOR TO FRANCIS A. BRUNER, INC., OF PHILADELPHIA, PENNSYLVANIA, A CORPORATION OF NEW JERSEY.

DESIGN FOR A WINDOW DRAPERY.

Application filed February 18, 1925. Serial No. 12,416. Term of patent 7 years.

To all whom it may concern:

Be it known that I, ROBERT J. MURRAY, a citizen of the United States, residing in Philadelphia, in the county of Philadelphia and State of Pennsylvania, have invented a new, original, and ornamental Design for a Window Drapery, of which the following is a specification, reference being had to the accompanying drawing, forming part hereof.

The figure is a face view of a portion of a window drapery showing my new design, the lower end of which is provided with

what may be described as a border while the other portion thereof is repeated throughout the remaining length of the drapery. The upper end of the drapery terminates without a border, as indicated in the drawing.

I claim:

The ornamental design for a window drapery, substantially as shown.

In testimony whereof I have hereunto signed my name this 17th day of February, A. D. 1925.

ROBERT J. MURRAY..
